UNITED STATES PATENT OFFICE.

PAUL FLEMMING COX, OF CHICAGO, ILLINOIS, ASSIGNOR TO THE COX
TYPE SETTING MACHINE COMPANY, OF SAME PLACE.

TYPE-DISTRIBUTING MACHINE.

SPECIFICATION forming part of Letters Patent No. 578,216, dated March 2, 1897.

Application filed June 10, 1896. Serial No. 594,989. (No model.)

To all whom it may concern:

Be it known that I, PAUL FLEMMING Cox, of Chicago, in the county of Cook and State of Illinois, have invented certain new and useful Improvements in Type-Distributing Machines; and I hereby declare that the following is a full, clear, and exact description thereof, reference being had to the accompanying drawings, which form part of this specification.

This invention is an improvement upon the type-distributing machines described in Letters Patent Nos. 550,553 and 550,555, granted to me November 26, 1895; and the object of this invention is to simplify the construction of the operative mechanisms of such machines and to render the working parts thereof easily accessible at all times.

The invention also has especial reference to the mechanism for imparting an intermittent movement to the test-plates, and to the mechanism for insuring register of the test-plates with the type-channels.

The invention is best summarized in the claims forming part of this specification, and the accompanying drawings illustrate the improved machine, which is hereinafter described in detail.

In said drawings, Figure 1 is a central vertical section through the complete machine. Fig. 2 is an enlarged plan view of the test-plate-moving devices. Fig. 3 is an enlarged vertical section on line 3 3, Fig. 2. Fig. 4 is an enlarged plan view of the test-plate-registering devices. Fig. 5 is a vertical section on line 5 5, Fig. 4. Fig. 6 is a detail vertical section through type-reservoir and test-plate. Figs. 7 and 8 are detail views of parts of the casting G. Fig. 9 is a detail view of part of casting g. Fig. 10 is a view of the pusher-plate-operating devices detached.

Upon a hollow vertical standard A is fixedly mounted a circular casting B, on top of which is supported a rotatable annulus b, having a series of square-cut equidistant notches b' in its periphery.

Mounted on and revolving with annulus b is a circular casting C, provided with a bell-skirt flange C' to support type-line holders, and mounted on casting C is a circular test-plate D, provided with notches D' in its pe-

riphery, over which are fitted the test-plates, and below and working into each notch is a type-pusher E, which are connected to and operated by a vertically-movable plate F, interposed between the test-plate disk D and casting C, as shown. The parts C, D, E, and F are constructed and operated substantially as described in my Patent No. 550,553, and it is not necessary to particularize their construction herein.

Above test-plate D is the stationary undistributed-type reservoir, which is formed, for convenience, in two parts, to wit: a lower circular part g and upper part G, both being centered on, supported by, and fixedly secured to the standard A. The type-channels of the reservoir, however, are principally formed by removable type-holders H, herein-after described. The part g has a series of vertical type channels or slots g' in its periphery, corresponding in number and distance apart to the test-plates on disk D. (See detail Fig. 6.) At the outer side of each slot g' is a registering-plate g², which brings the type descending into and through slots g' into exact register longitudinally with slots D' in disk D. The upper part G has an exterior flange G' at bottom and another, G³, at top, flange G' being vertically slotted, as at G², coincident with the slots g' in part g. Flange G³ is wider than flange G' and has slots G⁵ in it coinciding with the slots G² g', and exterior to these slots are slots G⁴, which are adapted to receive the edges of the type-line holders H. (See detail Fig. 7.) The slots G⁴ might be considered enlargements of slots G⁵. The upper end of part G is closed by a circular plate G⁶.

The holders H are U-shaped in cross-section. Their backs or bottoms project at one end, as at H', and are rounded, as shown, so as to fit to the bottoms of slots D and allow pushers E to work thereover, (see Fig. 1,) and the bottoms are cut out or slotted, as at H², at the other end of the holder to enable the holders to be placed upon the type-channels of my type-setting machine, and for the further purpose of enabling the attendant to see when any holder containing undistributed type placed upon the reservoir is empty. The type-line holders H, in fact, are adapted

to be first automatically filled with undistributed type by the machine described in my Patent No. 550,553, and then placed upon the reservoir of the present distributor, forming 5 the principal type-channels thereof, as indicated in the drawings. Then they can be placed upon the skirt C' and filled with distributed type and then placed upon the type-setter to supply distributed type to the channels thereof, as described in my application for 10 a type-setting machine filed herewith. The type-line holders are thus interchangeably useful in four positions and with three different machines.

15 By reference to Figs. 6 and 9 it will be seen that the upper ends of slots g are widened, as at g⁴, to receive the lower ends of holders H, which are slipped therein, as indicated in Figs. 1 and 6, the inner edge of the holder 20 abutting against the flange G' and the upper end of the holder fitting into the slots G⁴, as shown, so that each holder is held in upright position.

15 The *test-plate-moving mechanism*.—On one side of casting B is a bracket B', in which is journaled a short vertical shaft I, having a bevel-gear I' on its lower end meshing with a bevel-gear K' on the end of a horizontal shaft K, extending through standard A and 25 journaled in bearings B³ of casting B. On the shaft I above bracket B' is fixed an eccentric i, whose strap i' is pivotally connected to the end of a horizontal lever i², pivoted on the standard A above casting B and extending 30 beneath the annulus through a slot in the upper edge of disk B, as shown. Above the eccentric i is a cam-disk J, (as shown the eccentric is attached to the hub of the cam,) having a cam-groove J', which is engaged by a 35 friction roller or stud J², attached to a bar J³, which is pivoted at one end to the short arm j' of a bell-crank dog j, pivoted at its bend on lever i², close to the periphery of annulus b, the toothed arm of the dog extending toward 40 and slightly above the eccentric, as shown in Figs. 2 and 3. The other end of bar J³ is bifurcated to embrace the reduced upper end of shaft I and is kept down by means of washer I² and nut I³. The cam J is so 45 constructed that during forward movement of lever i² dog j remains stationary with relation to the lever. As eccentric i approaches dead-center, however, the dog is thrown into engagement with a notch of annulus b by the 50 action of cam J, remaining engaged during the back stroke of lever i² and thereby rotating annulus b and the test-plates, &c., supported thereon one notch. At end of back stroke the dog is thrown out of engagement 55 with the notch and held out during the forward movement of lever i². Thus an intermittent regular movement is imparted to the test-plate from the continuously-running shaft K. This mechanism is obviously useful 60 in many machines where a regular gradual intermittent movement of a part is desired.

65 The mechanism for registering test-plate

disk with type-channels.—On the other end of shaft K is a bevel-gear K², meshing with a bevel-gear L' on the lower end of a short 70 vertical shaft L, journaled in a bracket B³ on the side of casting B opposite bracket B'. On the upper end of shaft L is a cam-disk L², the groove in which is engaged by a friction-roller l² on a horizontally-sliding bar l, 75 whose outer end is guided in guide l³, attached to bracket B³. (See Figs. 4 and 5.) The inner end of bar l is pivotally connected to one arm of a bell-crank lever M, connected at its bend by a lock-hinge joint to 80 the end of a vibrating lever m, which is pivoted at its other end on a bolt m', secured in a slot N' in a bracket N, attached to the casting B, by means of the opposite adjustable tap-bolts n n, by which the pivot m' of lever 85 m can be adjusted. Lever m has a tooth m², adapted to engage a notch b' in annulus b, and the short arm M' of lever M is adapted to enter another notch of the annulus at the same time. A coiled spring M² is interposed between the lever m and long arm of lever M, so as to normally push the long arm of lever M away from lever m as far as the lock-hinge 90 will allow, thereby bringing the short arm of the lever M nearer to tooth m². 95

When dog j is about to disengage a notch b', the cam L² moves bar l inward, thereby pushing levers M and m inward and causing the teeth M' m² to easily enter adjoining notches in annulus b. Then the farther inward movement of bar l rocks lever M on lever m, compressing spring M², and tooth M' forces the annulus b tight up against tooth m², which is adjusted so as to hold the annulus exactly at the registering-point. Then 105 when dog j is about to engage a notch b' cam L² draws bar l outward, allowing the spring M² to expand and thus rock lever M on lever m and loosening the grip of teeth M' m² on the annulus. When spring M² has expanded as 110 far as the lock-hinge will allow, the farther outward movement of bar l draws levers M m entirely away from the annulus b, and then the dog j begins to turn it. Thus the operations of the test-plate moving and registering 115 mechanisms alternate in proper order.

The registering mechanism can be adjusted with the greatest nicety, as will be obvious from the drawings, and is useful in many machines.

120 Shaft K is driven in any suitable manner. As shown, it has a bevel-gear K³ on it meshing with a bevel-gear k' on the lower end of a vertical shaft k within the standard A, shaft k extending up through a central bearing in top plate G⁶ and having a bevel-gear k² on its upper end meshing with a bevel-gear O' on a short shaft O, journaled in brackets on top of plate G⁶ and driven by gears O² o' from a driven shaft o, also journaled in 125 brackets on top of plate G⁶, shaft o having friction and idler pulleys o³ o² on its end for the power-belt.

130 The pusher-actuating plate F is vibrated

up and down by means of rods F' , connected at top to a collar F^3 on the hub of plate F and at bottom to the bifurcations of a lever F^2 , pivoted upon a bracket attached to the 5 side of the standard below shaft K . The end of lever F is connected to a slide-rod f , having a looped upper end embracing shaft K , so as to be guided thereby in its vertical movements, and on said slide is a friction- 10 roller f^2 , engaging a cam-groove in a disk K^4 , keyed on shaft K , as shown in Fig. 1.

So far as the operation of distributing type is concerned it takes place as described in my 15 patents aforementioned, and the operations 20 of the novel mechanisms in the present distributor are obvious from the drawings, or have been sufficiently explained. It will be observed, however, that the undistributed-type reservoir is non-rotatable, the type to be 25 distributed are contained in the holders H , which are set in position over slots g' , as shown, and when the operator sees that the types have all passed from the holder he removes it and replaces it by another. This can 30 be done without interrupting the operation of the machine, as the channels g' hold enough type to enable the operation to continue while the holders are being changed.

Having thus described my invention, what 35 I therefore claim as new, and desire to secure by Letters Patent thereon, is—

1. The combination with a notched casting; a lever pivoted on a support beside the casting and having a tooth adapted to engage a notch 35 thereof, a lever pivoted on the first lever having a bent arm adapted to engage another notch of the annulus, and means substantially as described for moving the toothed levers into engagement with the notches, then forcing 40 the teeth of the levers apart; then moving them together and withdrawing them from the notches; substantially as and for the purpose set forth.

2. The combination of the notched casting, 45 the pivoted lever as m , the lever as M pivoted to lever m , and means for moving said levers into and out of engagement with the notches of the casting and rocking one lever upon the other, substantially as described.

50 3. The combination with the notched casting; the pivoted lever as m , the lever M pivoted to lever m ; the spring M^2 and means substantially as described for operating said levers, substantially as and for the purpose described.

55 4. The combination of the notched annulus, the levers as m , M , arranged substantially as described; with the cam-disk, and the sliding bar for vibrating said levers, and a spring for 60 rocking lever M on lever m all substantially as and for the purpose set forth.

5. The combination with the casting, the adjustable toothed lever, the rocking lever pivoted to the swinging end of the adjustable 65 lever; and means for swinging said levers toward and from the annulus and rocking the rocking lever, substantially as described.

6. The combination of the notched annulus, the adjustable lever as m , the rocking lever as M pivoted on lever m ; the spring M^2 , the 70 slide l and cam-disk L^2 , all substantially as and for the purpose described.

7. In a type-distributing machine, an undistributed-type reservoir, consisting of the casting g having slots g' , with the casting G 75 having slotted flanges G' , G^3 , all substantially as and for the purpose described.

8. In a type-distributing machine, the combination of the reservoir having slots g' in its lower end, and flanges G' , G^3 , above said slots 80 g' , said flanges being slotted at points coincident with slots g' ; with the removable type-line holders H fitted over slots g' and retained by the slots in the flanges, all substantially as and for the purpose described. 85

9. In a type-distributing machine the combination of the standard, the casting B and the type-reservoir supported on said standard; and the rotatable test-plate disk supported on said casting; with means for rotating the 90 test-plate disk, and the mechanism for registering the same with the channels of the reservoir, comprising the levers m , and M , the slide l , and cam L^2 , and means for rotating said cam, all substantially as and for the pur- 95 pose described.

10. The combination of the type-reservoir, and test-plate disk, substantially as described, and the mechanism for rotating the disk, comprising the shaft I , eccentric i , lever i^2 , dog j , 100 bar J^3 , and cam J' , substantially as described, at one side of the disk; and the mechanism for registering the disk and reservoir, consisting of the shaft L , cam L^2 , bar l , and levers M , m , substantially as described; with 105 the horizontal shaft K , geared at its opposite ends to shafts I and L respectively, and mechanism for rotating said shaft, all substantially as and for the purpose set forth.

11. In a type-distributing machine, the combination of the stationary type-reservoir mounted on a central hollow standard; the rotatable test-plate disk D below the reservoir, the rotatable type-holder support C connected to the disk; the type-pushers E in the 115 slots of the disk; the pusher-operating plate F ; the notched annulus b , and the bottom casting B fixed to the support and upholding the parts b , C , D , and F ; with the shaft K transfixing the support below the casting B 120 and suspended from the latter, the disk-rotating mechanism supported on one side of casting B and driven from one end of shaft K ; the disk-registering mechanism supported on the opposite side of casting B and driven 125 from the other end of shaft K ; the mechanism for vibrating plate F , also driven from shaft K ; and the vertical shaft and gearing substantially as described for driving shaft K , all substantially as and for the purpose 130 described.

12. The combination of a rotatable notched casting, a swinging lever; and a dog on said lever adapted to engage the notches of the

casting; with the rotating shaft parallel with the axis of the casting, the eccentric thereon and connections between said eccentric and lever for vibrating the latter, a cam on said shaft and a sliding plate or bar pivoted to the dog and having a pin engaging the cam whereby the dog is thrown into and out of engagement with the notches of the casting at the proper times during the reciprocations of the lever, substantially as and for the purpose described.

13. The combination of the horizontal rotatable notched annulus; the horizontally swinging lever i^2 ; and the dog j pivoted on the lever; with the vertical rotating shaft, the eccentric i thereon, the eccentric-strap i' , connected to the lever; a cam-grooved disk J on said shaft, and the sliding bar J^3 operated by said cam and pivotally connected to

the dog j , substantially as and for the purpose 20 described.

14. In a type-distributer, the combination of the supporting-standard, the bifurcated vibrating pusher-plate F , the oscillating lever as F^2 pivoted on the standard and connections 25 between the lever and plate for vibrating the latter; with the rotary shaft K carrying cam-disk as K^4 , the slotted slide-rod embracing said shaft and operated by said cam, and connected to and actuating lever F^2 , all 30 substantially as and for the purpose described.

In testimony that I claim the foregoing as my own I affix my signature in presence of two witnesses.

PAUL FLEMMING COX.

In presence of—
JAMES A. WOOD,
A. A. McEWEN.
